UNITED STATES PATENT OFFICE

1,999,968

DISPLAY RACK

Thomas Nickel, Chicago, Ill., assignor to The Curtiss Candy Company, Chicago, Ill., a corporation of Illinois

Application August 18, 1934, Serial No. 740,407

2 Claims. (Cl. 206—44)

The present invention has to do with a display rack made from sheet material and disposed upon and secured to the edges of an open box.

The objects of the invention include, among others, the provision of the following:

An unique display rack;

Novel means for attaching a display rack to a box;

An improved structure which provides advertising space and serves as a rack for articles of merchandise;

An unique structure which provides advertising space and serves as a rack for articles of merchandise.

These objects and such other objects as may hereinafter appear are obtained by the novel construction, unique arrangement, and improved combination of the several elements which constitute the invention, two forms of which are illustrated in the accompanying one sheet of drawing hereby made a part of this application, and in which:

Figure 1 is a plan view of a blank used to produce one embodiment of the invention;

Figure 2 is a front view of a box of candy bars having the display device illustrated in Figure 1 attached thereto;

Figure 3 is a side elevation of the form of the invention shown in Figures 1 and 2 and illustrating the manner of its attachment to a box;

Figure 4 is a plan view of the blank used for producing a second form of the invention; and

Figure 5 is a section on the line 5—5 of Figure 4 of a display rack formed by folding the blank shown in Figure 4.

Like reference characters are used to designate similar parts in the drawing and in the following description of the invention and the two embodiments thereof.

The blank shown in Figure 1 comprises a sheet of cardboard or the like having scores and slits therein. The blank comprises a main body 10, a wing 11, a second wing 12, and a base 13. The main body 10 may have at its front advertising matter. The advertising thereon should be arranged in relation to the articles to be suspended on said main body. The outer surfaces of the sides 11 and 12 also may contain suitable advertising matter.

Sections 11 and 12 are hinged to section 10. The hinge is multiple and is defined by a series of scores 14 and 15, the scores 14 separating section 11 from section 10, and the scores 15 separating section 12 from the main body 10. Cuts extend from adjacent ends of the scores into the

body of section 10. Each of these cuts comprises a top curved portion 16 beginning at the bottom of each score, a vertical section 17 depending from cut 16, and a lower cut 18 which also may be curved adjacent its near end and which extends from the lower end of slit 17 to the upper end of the adjacent score. There are at each side of the rack illustrated four series of such cuts each of which produces a rack 19 which is cut from the main body 10 and is integral with 10 and in alignment with the side member, 11 or 12.

The side members 11 and 12 are folded upon the scores 14 and 15, respectively, whereupon the racks 19 are made to project forwardly of body 10. When projecting, the racks 19 form suitable supports for candy bars 20 as shown.

Main body 10 is separated from base 13 by a score 21, the ends of which terminate in slits 22 and 23. The slits may form the bottom edge of the lowermost opposed racks 19 in place of the cut 18. Section 13 is disposed in a vertical position in a box 26 and is positioned at the side or front of the box being inserted between the wall of the box and the merchandise in the box.

Each of the wings 11 and 12 adjacent its rear edge has a notch 24 and 25. The notches 24 and 25 engage the wall of the box 26 opposite that against which base 13 is disposed. With the base 13 resting upon the bottom of a box 26 and disposed in parallelism with the side 27 thereof, and the notches 24 and 25 engaging the side 28 of the box, the device is maintained against collapse and in a predetermined position upon the box 26. Candy bars 20 or other merchandise taken from the box 26 is put on display in the rack 19 by having the ends of the bar rest on the racks 19. Such items will overhang the front of the box and attract attention. The score 21 permits of the tilting of the body 10 and of the sides 11 and 12 at a slight angle to base 10 and over the box 26.

The device illustrated and described may be used either at the front or at the end of a box by changing the length of the wings 11 and 12 and the dimensions of base 13.

Figures 4 and 5 illustrate a display rack that is identical with that illustrated in Figures 1 and 2 and 3 except for the base. The device illustrated in Figures 4 and 5 has a base which may be disposed on a flat surface as the top of a show case. These parts in Figures 4 and 5 that are identical with parts in Figures 1, 2, and 3, are given the same reference characters with the added letter "a".

In place of the base 13 and notches 24 and 25

of Figures 1, 2, and 3, the device shown in Figures 4 and 5 comprises base members 30, 31, and 32. Member 30 is separated from part 10a by a score 21a. Member 31 depends from the side 11a and is separated therefrom by a score 33, and base 32 depends from side 12a, and is separated therefrom by a score 34.

There is a slit 35 in member 31 and a tongue 36 is cut in base 32. The tongue 36 is inserted into the slit 35 to hold the sides 11a and 12a in angular position, the member 30 preferably resting upon the members 31 and 32 although it may be disposed therebeneath. An oblique position for side 10a is obtained by making the score 33 and 15 34 oblique to the scores which separate the parts 10a and 11a, and 10a and 12a.

What is claimed as new and is desired to be secured by Letters Patent of the United States is:

1. A display device of sheet material for use 20 in connection with the open side of a sheet material box and comprising a front member, a base separated therefrom by a score and disposable in parallelism with and in contact with one side of such box, and two side members separated from 25 said front member by alternate scores and slits,

the slits defining tabs of the material of said front member and integral with said side members, said side members having notches and being foldable on such scores to register the notches with the opposite side of such box, the tabs remaining in alignment with said side members and protruding forwardly from said front member when said side members are folded back.

2. A device of sheet material for use in connection with the open side of a sheet material rectangular box and comprising a front member, a base separated therefrom by a score and disposable within such box and parallel to and in contact with one side thereof, and two side members separated from said front member by alternate scores and slits, the slits defining tabs of the material of said front member and integral with said side members, said side members having notches in their under edge and being foldable on such scores to engage the top edge of the side of such box away from said base, the tabs remaining in alignment with said folded back side members and protruding forwardly from said front member to provide article display racks.

THOMAS NICKEL.
